UNITED STATES PATENT OFFICE.

ELMER HASLETT, OF SAN FRANCISCO, CALIFORNIA.

MASSAGE OUTFIT.

Application filed February 23, 1926. Serial No. 90,098.

This invention relates to massage outfits. Heretofore it has been customary to provide containers for massage creams or substances, and entirely separate devices by which the 5 massage substances may be worked into the skin. The massage cups or devices after use retain more or less of the massage cream or substance on their contact surface, and if exposed will collect dust and will frequently 10 soil surfaces upon which they are placed. Frequently the massage creams or substances are medicated, and if left exposed to the air will lose some of their medical properties.

An object of this invention is to provide an 15 improved massage outfit with which loss of medical properties of the massage substances or creams will be prevented; with which danger of soiling of the surface upon which the outfit is supported will be reduced or 20 prevented; and which will be exceptionally simple and convenient, and relatively inexpensive.

Various other objects and advantages will 25 be apparent from the following description of two embodiments of the invention, and the novel features will be particularly pointed out hereinafter in connection with the appended claims.

In the accompanying drawing: 30 Figure 1 is an elevation, partly in section, of an outfit constructed in accordance with the invention.

Figure 2 is an elevation, also partly in section, of another outfit also constructed in 35 accordance with the invention, but illustrating another embodiment thereof; and

Figure 3 is a top plan of the outfit shown in Figure 2.

In the embodiment of the invention illustrated in Figure 1 a suitable container 1 is provided for receiving the massage cream or substance 2, and the open face of the container is normally closed by a cover 3. This cover 3 is also utilized as a massage instrument, and for that purpose is provided with a peripheral flange 4 of soft, flexible, resilient rubber which fits over and closely embraces the open end of the container. A projecting portion 5 of the cover 3 serves as 50 a handle by which the cup may be manipulated for massaging purposes after it has been removed from the container.

The projecting portion 5 may also have an angular flange 6 of soft, flexible, resilient rubber so that it may also be employed as a massaging instrument when desired. Pref-

erably the flange 6 is of less diameter than the flange 4. The body portion of the cover may be formed of any suitable material, but preferably the entire cover, including the flanges 4 and 6, is formed of a single molded body of a soft, flexible, and resilient rubber, and the extreme edges of the flanges 4 and 6 are preferably flared outwardly so as to facilitate their massage action in use. The 60 two faces of the cover within the flanges are made noticeably concave, so that the upper and lower ends or faces of the body will form two vacuum massage cups of different dimensions.

The container 1 may be formed of any suitable material, but preferably is provided with a lining 7 of radio-active material, so that the radium emanations therefrom, will penetrate and be absorbed by the massage substances or creams which are within the container. Such a lining may be formed, for example, by mixing ground radium bearing ore with a suitable porous binder, and cementing or otherwise securing it as a lining to the container 1. For this purpose the container 1 may be advantageously formed of pottery, and the porous clay like binder carrying the radium bearing ore united thereto by burning the entire container, as usual in pottery manufacture.

It has been found that massage creams or substances placed in a container of this type after a few hours become radio-active, by reason of their absorption of the radium emanations from the lining containing radium ore. The medical properties of a radioactive substance are well known, and it has been found that such massage substances have greater efficacy than similar substances which are not radio-active and yet are perfectly safe for use by everyone.

In the use of such an outfit the cover is removed and the massage cream applied to the skin, and worked in by the use of one or the other massage cups of the cover. During such use the interior or concave face of the larger cup of the cover becomes covered with the massage substances or creams, and when the cover is re-applied to the container in order to close it, the cream or massage substance which is carried by the cover will cause a very tight adherence or seal between the cover and the container, and very effectively prevent the escape of the medical ingredients of the massage substances or cream, particularly when such creams or sub-

stances contain volatile ingredients. When the covers are used to massage around the facial features, for example, it may be more convenient to use the smaller cup and, therefore, by the provision of the double cup of different sizes, one may select for use whichever cup is most convenient and suitable for massaging any particular portion of the body.

10 After use, the cover is replaced upon the container and, therefore, is not likely to be placed upon surfaces which it might soil by reason of the adhering cream, and there is more assurance that the container will always be closed in order to prevent the loss of any of its properties. The interior of the larger concave face, which is largely used, and which retains considerable cream, will be concealed when the cover is upon the container, 15 and therefore, will collect and hold less dust from the air, than it would if left entirely exposed. Thus with such an outfit there is little danger of soiling various other objects or surfaces, or of deterioration or losses of the valuable ingredients of massage creams. 20 Either end of the cover serves as a convenient handle when the other end is used as a massage cup.

In Figures 2 and 3, a similar container 1 is shown as provided with a massage cup cover 8 of a slightly different construction. This cover 8 is also provided with the soft, flexible, resilient rubber flange 9 which embraces the open end of the container and serves to close it, and may have a suitable projecting handle portion 10 which is connected to the body of the cover by an undercut section 11, enabling one to obtain a firmer grasp upon the cover for removing or replacing it upon the container or while using it as a massage instrument. The handle portion 10 may also be flattened somewhat upon its periphery as at 12, to prevent the turning of the cup in one's hands while the cup is being used.

45 This combination cup and cover for the
46 container is also preferably formed of a sin-
47 gle molded body of soft, resilient rubber. Its
48 use will be obvious from a description of the
49 use of the other cover 3 of Figure 1. Since
50 the inside concave face of the top will be
51 greasy from use, all that is necessary to tight-
52 ly close the container, is to place the cup there-
53 on and it automatically forms an air tight
54 closure for the container.

55 It will be obvious that various changes in
the details, which have been herein described
and illustrated in order to explain the nature
of the invention, may be made by those skilled
in the art within the principle and scope of the
invention as expressed in the appended
claims.

I claim as my invention:

1. A massage outfit including a container for massage cream and the like, and a cover

for the container, said cover having a resilient rubber flange to form with the body of the cover a vacuum massage cup by which the contents of the container may be massaged into the skin of a patient; said cover engaging with the container, while closing it, upon the interior face of said flange, whereby the cream remaining in the interior of the flange of the cup of the cover after a massage will form a seal for the cover when the latter is forced upon the container to close it. 65
70
75

2. A massage outfit including a container for massage cream and the like, and a cover for the container, said cover having a resilient rubber flange to form with the body of the cover a vacuum massage cup by which the contents of the container may be massaged into the skin of a patient; said cover engaging with the container, while closing it, upon the interior face of said flange, whereby the cream remaining upon said flange in the interior of the cup of the cover after a massage will form a seal for the cover when the flange of the cover is forced upon the container in tight engagement therewith to close it, the outer face of the cover having a projecting portion serving as a handle by which the cover may be applied to or removed from the container and manipulated for massage purposes.

3. A massage outfit including a container for massage cream and the like, and a removable cover for the container formed of molded, soft, resilient rubber, with a concave face end which telescopes over and fits and closes the open end of the container and which, when removed from the container, serves as a vacuum massage cup by which the container contents may be massaged into the skin of a patient, the cream remaining in the concavity of the cover after use of the latter as a massage cup forming a seal between the cover and container when the latter is closed by pressure of the cover thereon. 10 10 10

4. A massage outfit comprising a container for massage cream and the like, said container having an approximately cylindrical open end, and a removable cover for said container having a flexible soft resilient rubber flange approximately cylindrical adjacent its free edge which telescopes over and tightly fits the approximately cylindrical end of the container, to frictionally remain thereon, the cream remaining on the interior surface of the flange after use forming a seal between the cover and the container, said free edge, however, being somewhat flared outwardly to facilitate application of the cover to the container and to increase the tendency of the open end of the cover to stretch and flatten out when pressed against the skin during a massaging operation.

ELMER HASLETT.
